UNITED STATES PATENT OFFICE.

LEON EDWARD WHITLOCK, OF LEAVENWORTH, KANSAS, ASSIGNOR TO WESTERN ELECTRIC COMPANY, INCORPORATED, OF NEW YORK, N. Y., A CORPORATION OF NEW YORK.

TOOL FOR CLEANING ELECTRICAL-CONTACT SURFACES.

Application filed June 7, 1923. Serial No. 643,888.

To all whom it may concern:

Be it known that I, LEON EDWARD WHITLOCK, a citizen of the United States, residing at Leavenworth, in the county of Leavenworth and State of Kansas, have invented certain new and useful Improvements in Tools for Cleaning Electrical-Contact Surfaces, of which the following is a full, clear, concise, and exact description.

10 This invention relates to tools for cleaning surfaces and more particularly to a tool for simultaneously cleaning a plurality of electrical contacting surfaces.

In order to insure good electrical conduction between contacting surfaces employed in electrical apparatus it is essential that such surfaces be free of foreign material of an insulating nature. Precautions of this nature are especially necessary in telephone exchange equipment, where comparatively low voltage sources of current are employed. The operation of the various elements of telephone exchange apparatus insures that the contact surfaces are maintained free 25 from such foreign matter. However, when additional apparatus is installed, or when previously installed reserve apparatus is placed in use, it is sometimes necessary to remove any foreign matter which may have 30 collected upon contact surfaces thereof during the installation work or the period of disuse.

In some telephone exchange equipments of the machine switching type a member 35 moving along a predetermined path carries a plurality of resiliently supported contact members which selectively engage sets of terminals arranged in a banked formation.

It is an object of the present invention to 40 clean a plurality of surfaces adapted to be selectively engaged by a contact carried by a guiding member, by moving along such member an abrading tool for successively engaging and cleaning the surfaces.

45 Another object is to slidably engage a guiding member at any point in its length with a tool carrying a plurality of resiliently supported abrading members over a plurality of sets of contact surfaces, as the tool 50 is moved along the guiding member.

An additional object is to provide a tool which may be easily and readily attached to a member in the proper position to clean

contact surfaces placed adjacent to the member.

A further object of the invention is to expedite the cleaning of terminals adapted to be engaged by contact brush members in a machine switching telephone exchange by simulating with a cleaning tool the action 60 of the contact brush.

In order to attain these objects there is provided, in accordance with one embodiment of the invention, a pair of pivoted jaw members, each carrying at one end a plurality of resiliently mounted abrading members. A grooved split block member separable in response to the opening of the jaws to permit its embracing a support, serves to properly position the abrading members. 70 Thus as the tool is moved along the support, the surfaces of contact members arranged in a plurality of rows are properly cleaned of all foreign matter to insure good electrical contact between such members and 75 co-operating brush contacts carried by the support in the normal operation of the apparatus with which the surfaces are associated. A gauge attached to one jaw member serves to limit the extent of movement of 80 the tool in one direction so that it is effective throughout its movement.

These and other features not specifically mentioned will appear from the following description and the accompanying drawing, 85

Fig. 1 of which shows an end elevation, in section, of a portion of a framework supporting a bank of multiple terminals in a machine switching telephone exchange with the tool in its operative position;

90 Fig. 2 is a fragmentary sectional view along the line 2—2 of Fig. 1, and

Fig. 3 is a fragmentary perspective view of the tool showing in detail the abrading members and the means for attaching them 95 to the tool.

Referring to the drawings in detail in which similar reference characters denote similar parts throughout the several views, upper and lower horizontal T irons 10 and 100 11 are supported in any suitable manner from the remainder of the framework (not shown) and support top and bottom extension flat members 12 and 13 respectively. Placed between the members 10 and 11 and 105 supported in any suitable manner upon the

remainder of the framework is a bank of multiple terminals designated generally by the character 20. The bank is composed of top and bottom members 21 and 22 respectively, and a plurality of sets of electrical contacting strips 23, 24, and 25, the adjacent individual strips as well as the sets of strips being separated by layers of suitable insulating material 26, all of these strips and members being clamped together to form one compact unit by bolts 28 passing therethrough. Adapted to selectively contact with the terminal portions projecting from one side of the strips 23, 24, and 25 in the operation of the telephone exchange apparatus is a contact brush 30 fixed to and carried by a conduit 31, which serves to enclose the conductors connected to the brush as well as to guide the brush in its movement. Although the invention is not limited thereto, the contact brush 30 and its supporting conduit 31 may be of the same general type as disclosed and claimed in Patent 1,123,695, issued January 5, 1915 to E. B. Craft and J. N. Reynolds. A fixed vertical rod 33 may have attached thereto an arm 35 for engaging an arm 36 to trip the brush 30 as it moves upwardly in a manner somewhat similar to that described in the above mentioned patent. Thus the projecting contact arms of the brush slide over guiding members 38 attached to the lower member 22, and as the brush continues in its upward movement, the contact surfaces thereof successively engage the edges of the projecting terminals of the strips 23, 24, and 25, constituting the different sets of terminals in the bank. Inasmuch as the construction and operation of the brush and the associated apparatus is not essential to an understanding of the invention, no further details relative to these structures need be given.

The jaw members 40 and 41 are interconnected by a pivot pin 42, carrying a spring 43, which bears against and maintains the handle portions of the jaw members separated. Secured by screws 46 to the forward ends of the members 40 and 41 respectively, are blocks 44 and 45, preferably of vulcanized fiber or other suitable insulating material, and provided with co-operating semi-circular vertical grooves 47 and 48 adapted to slidably embrace the exterior of the conduit 31. Insulated resilient spring members 50 and 51 are mounted upon and insulated from the forward end of the member 40, and corresponding spring members 52 and 53 are similarly mounted on the forward end of the member 41. Each of the resilient members 50 to 53 inclusive, has loosely mounted thereon by pivot pins 56 a cleaning member 57 provided with an abrading surface, as more clearly shown in Fig. 3, for engagement with the edges of the terminals projecting from the bank 20. A gauging member 59 attached

to the arm 40 serves to engage the upper plate 12 when the tool has been moved to the upper contact surfaces of the bank, and thus limits the upward movement of the tool so that the abrading members do not move beyond the bank, the uppermost position of the tool being as shown by dotted lines in Fig. 1.

It is evident that the continually wiping action of the contact surfaces of the brush 30 as they move along the terminals of the bank maintains the surfaces in good contacting condition. However, when it is desired to place into service a bank of terminals which has been held in reserve for a considerable period of time, it is sometimes desirable to rapidly and positively clean such terminals before they are placed in service. In such a case the handle portions 40 and 41 are moved toward each other against the action of the spring 43, thus separating the forward ends of the jaw members and the split block members 44 and 45, and permitting the positioning of the tool at the bottom of the bank as shown in Fig. 1. In this position the split block members 44 and 45 loosely embrace the conduit 31 and properly position the abrading surfaces 57 carried by the arms 50 to 53 inclusive, against the edges of the projecting terminals in the bank, the abrading members being loosely pivoted on the resilient arms as shown, and the tension of the arms being so adjusted that the proper abrading action is produced. The tool is then moved upwardly along the conduit 31, thereby cleaning the edges of all of the terminals in vertical alignment with each of the abrading members. When the gauge member 59 strikes the underside of the upper plate 12, if the surfaces of the terminals are properly cleaned, the tool may then be removed by pressing the handle portions of the jaw members 40 and 41 together and withdrawing it from its engagement with the conduit 31 and the terminals of the bank. In case the surfaces do not appear to have been sufficiently cleaned, the tool is again positioned as shown at the bottom of the figure and the operation is repeated. The tool as shown is especially adapted to insure the contact surfaces of the bank being in perfect electrical conducting condition by simulating as much as possible the wiping action of the brush contacts normally traversing these surfaces in the operation of the telephone exchange equipment. Inasmuch as the contact plates 23, 24, and 25 in some instances may be connected electrically with working portions of an exchange, all parts of the tool designed for contacting therewith are insulated from each other, as well as from the framework upon which the apparatus is mounted.

What is claimed is:

1. In a tool for cleaning a plurality of

- contact surfaces arranged for successive engagement by a movable contact terminal carried by a guiding member, means slidably engaging the guiding member, a resilient 5 arm supported therefrom and abrading means supported therefrom for successively engaging the surfaces in response to a movement of the means along the guiding member.
- 10 2. In a tool for cleaning a plurality of contact surfaces arranged for successive engagement by a movable contact terminal carried by a guiding member, means slidably engaging the guiding member, a resilient 15 arm supported therefrom and an abrading member pivotally supported by the resilient arm for successively engaging the surfaces in response to a movement of the means along the guiding member.
- 20 3. In a tool for cleaning a plurality of contact surfaces arranged adjacent to a guiding member, a pair of pivotally interconnected jaw members for slidably engaging the guiding member, and means supported 25 by one of the jaw members for slidably engaging and thereby cleaning the contact surfaces as the jaw members are moved along the guiding member.
4. In a tool for cleaning a plurality of sets of contact surfaces arranged adjacent to a guiding member, a pair of pivotally interconnected jaw members for slidably engaging the guiding member, and a plurality of means supported by the jaw members for simultaneously engaging the surfaces of one set of contacts and movable with the jaw members along the guiding members to successively engage the surfaces of additional sets and thereby clean such surfaces.
- 40 5. In a tool for cleaning a plurality of contact surfaces arranged for successive engagement by a movable contact terminal carried by a guiding member, a pair of pivoted members, a normally closed split block attached thereto and separating in response to a relative movement of the members to slidably embrace the guiding member, and abrading means supported by the pivoted members simulating the engagement of the 45 contact surfaces by the movable contact terminal in response to the movement of the split block along the guiding member, thereby cleaning the contact surfaces.
- 55 6. In a tool for cleaning a plurality of contact surfaces arranged in sets for successive engagement by a multi-contact terminal moved by a guiding member in the operation of a telephone exchange, a pair of pivoted jaw members, means carried thereby for slidably engaging the guiding member, and a plurality of abrading means also supported by the jaw members and successively engaging the sets of contact sur-
- faces responsive to a movement of the jaw members along the guiding member. 65
7. In a tool for cleaning a plurality of contact surfaces arranged in sets for successive engagement by a movable multi-contact terminal carried by a guiding member, means slidably engaging the guiding member, a plurality of resilient arms supported thereby corresponding in number to the surfaces in each set, and abrading means supported from each of said arms for successively engaging the corresponding surfaces 70 in the sets in response to a movement of the means along the guiding member.
8. In a tool for cleaning a plurality of contact surfaces arranged in sets for successive engagement by a movable multi-contact terminal carried by a guiding member, a pair of pivoted jaw members, a grooved split block member carried by each of the jaws and co-operating to slidably embrace the guiding member, a plurality of resilient 80 arms supported by each of the jaw members, and abrading means supported by each arm to successively engage the corresponding surfaces of the sets in response to a movement of the split block member along the 85 guiding member.
9. In a tool for successively cleaning a plurality of terminals arranged in a bank adjacent to a guiding member, extending beyond the bank resilient means supported 90 therefrom means slidably engaging the guiding member, abrading means carried by said means for successively engaging the terminals responsive to a movement of the first mentioned means along the guiding member, and means carried by the slidable means for limiting the movement thereof to prevent the abrading means moving beyond the bank. 95
10. In a tool for cleaning a plurality of contact surfaces arranged adjacent to a member, supporting means attachable to the member at any point thereof, resilient means supported therefrom and cleaning means mounted thereon and engaging and thereby 100 cleaning the contact surfaces when the supporting means is attached to the member. 105
11. In a tool for cleaning a plurality of contact surfaces arranged adjacent to a guiding member, supporting means attachable to the member at any point thereof, resilient means supported therefrom cleaning means mounted thereon, and means carried by the first mentioned means and co-operating with the member for positioning 115 the cleaning means to clean the contact surfaces. 120

In witness whereof, I hereunto subscribe my name this 29 day of May A. D., 1923.

LEON EDWARD WHITLOCK.
